TOOLHEAD WEDGE

Roy C. Bassett, Danbury, Conn.

Application April 29, 1948, Serial No. 23,943

2 Claims. (Cl. 306—33)

1

My invention relates to wedges for connecting tools and handles therefor.

The main purpose of my invention is to provide an improved wedge for fastening tools to their handles.

A further purpose of my invention is to construct a resilient wedge which is inserted into a handle and to secure the tool to the handle.

A further purpose is to form a wedge with longitudinal resilient arms which carry laterally projecting fingers for connection between a tool handle and a tool.

A further purpose is to groove the interior of a tool head for engagement of laterally extending fingers of a wedge member to form a permanent connection between the tool and its handle.

A further purpose is to use a resilient wedge unit in which the entering surfaces of the wedge are tapered for easy insertion in a tool handle fastening the tool to the handle.

A further purpose is to precut the end of a tool handle with arcuate surfaces which a resilient wedge will engage to force lateral extensions of the wedge laterally into slots or recesses formed in the tool to lock the tool permanently to the handle.

A further purpose is to provide a resilient wedge with a center transversely extending knife which is driven into the wood of the handle when the wedge is put to place to hold the tool and the handle together.

Further purposes will appear in the specification and in the claims.

I have found it desirable to provide a wedge unit for securely fastening tools such as hammers, axes, picks, sledge hammers and the like to their respective handles in such a manner that the tools themselves will not become detached from their handles for the life of the handle.

Referring to the drawings:

Figure 1 is a fragmentary side elevation partly in section showing a hammer head secured to a handle with my improved wedge driven into place in the head and in the handle.

Figure 2 is a perspective view of my improved wedge.

Figure 3 is a detailed elevation of the wedge shown in Figure 1.

Figure 4 is a fragmentary side elevation, partly in section, similar to Figure 1 but shown with the wedge in the act of being inserted in a slot in the end of a handle and with the wedge sides making engagements with the hammer.

Figure 5 is a fragmentary perspective of the

2

slotted end of the handle which cooperates with the handle socket of the tool.

In carrying out my invention I have preferred to show one form only of the different forms that my invention may assume. However, I have illustrated a form which is practical and convenient for insertion and which will meet the need of service.

In carrying out my invention I have found it desirable to precut the head end of a handle as clearly shown in Figures 1 and 4.

The handle 10 is precut at 11 in the form of a slit. This slit extends approximately the distance of the height of the tool and its handle engaging flange 12 integral with the tool 13, in the present instance shown as a claw hammer.

The center portion of the handle in the slit or precut portion 11 is arcuately curved outwardly at 14 and 15 on both sides of the center starting down from the end of the handle about one-third of the total height of the slit. The arcuate portions 14 and 15 curve outwardly to the side edges of the handle to approximately the bottom of the flange 12 of the head.

The tool has the usual handle socket 13', which is recessed at 16 and 17 on both sides of the handle near the bottom for reasons hereinafter described.

My improved wedge 18 is constructed of comparatively thin steel or other metal and is resilient and has laterally extending arms 19 and 20 with depending extensions 21 and 22 which have hooks 23 and 24 outwardly extending at their lower ends. The inner surfaces of the hooks 23 and 24 are arcuately shaped at 25 and 26.

Midway between the arms 19 and 20 and extending outwardly and downwardly therefrom is provided a knife wedge 27 which extends from both sides of the wedge unit 18.

I have found it desirable to arcuately curve the bottom portions 28 and 29 of the center web member 30 of the wedge. This will leave a comparatively thin extension 31 on each of the knife members 27.

The wedge arms 21 and 22 are tapered to produce a knife 32 at the bottom. The ends 33 and 34 of the knife wedge 27 are also tapered as clearly shown in Figure 3 to engage the sides of a tapering handle socket.

In Figure 4 I have shown my wedge in the act of being inserted into place to form the proper fastening of a tool and handle. In this view the wedge 18 is approximately halfway in the precut slot 11 and the downwardly extending arms 21 and 22 have been inwardly flexed due to the

flexing of the handle 10.

resiliency of the wedge. It will be noted that the hook ends 23 and 24 engage the interior walls 35 of the handle socket of the tool.

By forcing the wedge further into the slit 11 the arms 21 and 22 will have their arcuate edges 25 and 26 engage the arcuate portions 14 and 15 of the handle due to the arcuate shapes in the center of the slit 11, the arms 21 and 22 will gradually be forced outwardly and will also spring outwardly, and will finally have the hooks 23 and 24 engage in the recesses 16 and 17 in the tool itself. It will be noted that the interiors of the recesses 16 and 17 are cut angularly at 36 and 37 for proper locking engagement by the hooks 23 and 24. This permits subsequent tightening of the wedge by driving it in further.

It will be obvious that when the wedge is driven into place as described and the arms 21 and 22 have their hook ends engage in the recess that it will be very difficult for the tool to become separated from the handle.

In the meantime the knife wedge 27 will be forced into the solid end portion of the handle at right angles to the slit 11.

It will be evident that the slot 11 can conform as closely as desired to the sides of the arms of the wedge and can be itself of wedge configuration to the extent desired.

To aid in providing firm seating of the upper end of the wedge, the upper ends of the arms 19 and 20 are also made of wedge formation at 38 and 39 so that they will tend to straighten the motion of the wedge as it approaches its position of seating and frictionally engage against the walls of the handle socket.

In operation the handle will normally be pre-slotted as shown but will otherwise be imperforate so that the knife wedge 27 will strike into unslotted wood on either side of the slot 11. The handle will be fully inserted into the socket of the tool, and then the wedge will be driven in. The first action will be for the outer curve 25 and 26 of the forward edges to cam the arms 21 and 22 inwardly, thus flexing the arms as shown in Figure 4, especially at the portions 28 and 29, which are comparatively thin. The wedge is then driven into the slot 11 and will, of course, begin to expand the sides of the slot to some extent as it moves down, depending upon the point where it comes into tight jam engagement with the sides. Evidently, the forward edge of the knife wedge 27 will contact the end of the handle on either side of the slot 11 and drive into the handle, separating the parts of the same and spreading them laterally. When hook ends 23 and 24 have moved far enough down they will contact the upper portions of the recesses 14 and 15, on the wedge or slope portions 36 and 37. At the same position the arcuate portions 25 and 26 will jam against the curved walls 14 and 15 of the slots at 40 and 41, and after embedding themselves slightly in the wood the wedge will come to rest in seated position, preferably with the hook ends intermediate the length of the sloping upper walls 36 and 37 of the recesses 16 and 17. This is the initial position of the rest of the wedge. In the process of reaching this initial position the sloping outer ends 33 and 34 of the knife wedge 27 will frictionally engage the in-

terior of the handle socket, and also the sloping outer ends 38 and 39 will similarly engage the interior of the handle socket.

If after reaching the initial position, the wood should shrink or otherwise readjust and it is desirable to drive the wedge in further, this can be accomplished, and the hook ends will move down further along the sloping upper ends 36 and 37 of the recesses 16 and 17, allowing the arms 21 and 22 to expand further and spreading the upper portion of the handle to a greater extent.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a tool or the like, a tool head having a handle socket provided with wedge engaging recesses, a handle extending into the socket having a slot in the handle provided with curved walls, and a wedge having a wedge portion whose opposite edges are wedge shaped as well as its sides, having wedge arms resiliently connected to the wedge portion, the arms having opposite edges which are wedge shaped as well as the sides and having hook ends on the arms which are arcuately curved at their forward edges, which engage in the recesses of the handle socket and which jam against the curved walls of the handle socket.

2. In a tool, a tool head having a handle socket provided with opposed recesses having outwardly sloping walls directed toward the end opposite to the end from which the handle enters the socket, a handle extending into the socket, the handle being slotted and having opposed sloping walls in the slot opposite to the recesses, a wedge in the socket wedging apart portions of the handle and having a wedge portion, wedge arms resiliently connected to the wedge portion, and hook ends on the arms provided with curved forward edges which engage the curved walls of the slot in the handle, the hooks engaging the sloping walls of the recesses in the handle socket.

ROY C. BASSETT.
